ROUGHENING TOOL FOR WALLS OF CYLINDRICAL FINGER-GRIPPING HOLES OF BOWLING BALLS

Fred W. Berghorn, Rutherford, N. J.

Application August 24, 1949, Serial No. 112,118

3 Claims. (Cl. 145—114)

1

This invention relates to improvements in wall-roughening tool for finger-gripping holes of bowling balls.

The walls of the finger-gripping holes in bowling balls become smooth or glassy from the relative movement into and out of the same of the fingers of the bowler. This often causes a slipping of the fingers in whole or in part and prevents a proper grip on the ball by the fingers of the bowler in the operation of bowling and a consequent failure of control of the ball.

It is one of the objects of this invention so to roughen the side wall of the finger bore or hole as to avoid slippage of the fingers of the user and to enable a good grip on the ball in the operation of bowling to be always procured and, with this end in view, I provide a tool for roughening the side walls of the openings or holes of a bowling ball that receive the thumb and fingers of the bowler preferably at the portions of such walls that are engaged by the inside tough-skinned portions or pads of the fingers.

Another object of my invention is to provide a device of the character specified that will be so small, simple to operate and inexpensive that it will be possible for individual bowlers to purchase and use the same.

Still another object of my invention is to produce a device of the character specified that may be utilized to roughen only the side of the finger grip hole which is engaged by the inside tough-skinned pad portions of the fingers and to avoid any roughening of that portion of the finger-gripping holes or openings that is likely to touch the sensitive outer or upper portions of the fingers of the bowler.

Another object of my invention is to provide a tool of the character specified which will in operation contact with the cylindrical wall along three lines of contact spaced from each other to enable guiding at two lines and roughening by the tool along the portion contacted by the other of such lines of contact.

Still another object of my invention is to provide, in a tool of the character specified, a roughening member comprising a blade which is pivotally mounted at one of said three-lines of contact to cause pivoted movement thereof so as automatically to extend into parallelism with the axis of the hole at all times during roughening of holes of different diameters and to be maintained in such parallel relationship while the other two lines of contact will engage the wall of the cylindrical opening at two lines opposite to that portion of the wall which is being roughened.

2

Still another object of my invention is, in a device of the character specified, to provide a depth limiting member which will not scratch or mar the surface of the ball around the perimeter or edge of the finger-gripping opening being roughened by the tool.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a view in side elevation of my roughening tool mounted in a bowling-ball hole with its roughening blade in position for operation; and

Fig. 2 is a section on the line 2—2 of Fig. 1 looking in the direction of the arrows showing my tool in the hole and illustrating in dotted lines the segmental portion of the wall of the hole that may be roughened thereby; and

Fig. 3 is a view similar to Fig. 1 having the upper part of the tool-casing broken away and the roughening blade moved into inoperative position;

Fig. 4 is a view in side elevation on the line 4—4 of Fig. 3 looking in the direction of the arrow; and

Fig. 5 is a fragmentary section on the line 5—5 of Fig. 3 looking in the direction of the arrows.

Referring now to these drawings which illustrate a preferred embodiment of my invention, 10 indicates the casing of a roughening tool of my invention shown in operative position in a finger-gripping hole 11 of a bowling ball 12 fragmentarily shown.

In the preferred embodiment of my invention shown, my roughening tool comprises the enclosing casing 10 which, as illustrated, is formed of two parts 13 and 14 comprising a tool-holding part 13 and a tool-guiding part 14, the lower portions of which are movable toward and away from each other to enable contraction and expansion toward and away from each other of the wall-contacting portions of the tool. These parts 13 and 14 are, as shown, connected together at their upper ends, and as shown pivoted on a pivot 15. As illustrated, the tool-holding and guiding parts comprise U-shaped members movable telescopically in relation to each other to provide a tool casing. The casing parts are normally resiliently forced or pressed outwardly away from each other by a spring 16 wound around the pivot 15 at an intermediate portion and having its ends

16^a—16^b pressing against the inner walls of the U-shaped casing members **13** and **14**. Said members **13** and **14** have their spring-pressed movement limited by a slot and pin connection comprising a slot **14c** in the member **14** and a struck-up projection or pin **13c** on the member **13**.

The member **14** is preferably of a suitable width to provide corners **14^a—14^b** and the lower portion of the wall of the member **13** is suitably slotted at **13^c** and bent inwardly at opposite sides of said slit to provide parallel jaws **13^a—13^b** within which my roughening tool comprising an elongated blade **18** is mounted.

As shown, the blade **18** is pivoted intermediate its ends within the jaws **13^a—13^b** by a pivot **19** and is provided at one side edge with teeth **20**. The pivoting of this tool intermediate its ends on the pivot **19** enables the toothed edge **20** to be pressed against the wall **11^a** of the hole **11** in vertical parallelism with such wall and with the axis of the hole **11**.

In the preferred embodiment of my invention, the casing blade-housing and handle of my said tool is provided at one edge with an entrance-limiting projection **21** which, as shown, is preferably stamped out of the metal of the member **14** and has a rounded bottom surface **21^a** and an upwardly curved end **21^b**. The rounded bottom surface **21^a** rests on the edge of the hole of the bowling ball **12** and because of its rounded shape and the upturned end **21^b** prevents any scratching or marring of the bowling ball at the edges of the hole during the operation of my roughening tool in such hole.

In the embodiment of my invention shown, the roughening member comprises a relatively thin blade **18** which is movable about its pivot **19** through a semi-circular arc from operative to inoperative position on said pivot **19** as will be more particularly shown by a comparison of Fig. 1 with Fig. 3. Said blade when moved into its inoperative position is preferably enclosed with the housing members **13** and **14** and is fastened in such inoperative position by providing in one of the jaw members **13^a—13^b**, and as shown in the jaw **13^b**, an inwardly-disposed round projection or teat **22** formed by depressing the metal of the jaw **13^b** and adapted in closed position to engage with a hole **23** in the blade **18** to retain the same in said closed or turned position. In this position, the toothed edge of the blade **18** will be turned inwardly and extends within the enclosure. Said blade **18** is also preferably provided with a knurled edge **18^a** to provide a better grip for swinging the blade from inoperative to operative positions. Said blade **18** has, as shown at **18^b**, a portion of reduced width which in the operative position of the blade registers with the depressed teat **22** and thus avoids any fastening engagement between said blade and teat in said operative position of the blade. Such reduced portion **18^b** also allows sufficient freedom of pivotal movement to enable said blade to automatically assume a vertical position in parallelism with the wall of the hole within which the tool is inserted.

In the preferred embodiment of my invention the teeth **20** are preferably buttress-shaped and incline downwardly to permit a ready roughening of the wall surface while avoiding any excessive removal of material or cutting. This type of teeth also permits a ready slippage of the tool in an upward direction and also avoids any embedding of the same into the material of the wall.

In operation, assuming the tool to be in posi-

tion shown in Fig. 3, the bottom **18^a** of the blade is swung inwardly to permit initial pivotal movement to enable the top portion of the blade to be engaged by the fingers to swing same about its pivot and to cause it to assume the position shown in Fig. 1. The members **13** and **14** are then pressed by the fingers of the user inwardly toward each other to contract the width of the lower portion of the casing members into the position shown in dot and dash lines in Figs. 1 and 3. When so contracted, the tool may be readily inserted into the hole **11** of the bowling ball **12**. Upon release by the fingers of the user of the members **13** and **14**, the spring **15** will force the jaws and blade outwardly to cause the teeth of the blade to engage the wall **11^a**. Because of pivoting of the blade the edge of the blade having these teeth will always extend in parallel registration with the wall **11^a** and at the same time the corners **14^a—14^b** of the member **14** will engage the wall of the hole **11** at two spaced points opposite to the line of engagement of the blade with the wall.

The stop **21** will limit the insertion movement and upon a turning of the tool by the hand of the user, the wall **11^a** may be roughened along a segment **11^b** as shown in Fig. 2. The movement of the tool is thus adapted to roughen a specific part of the wall of the hole and the user may gauge this part so as to roughen only that part of the wall of the hole that is engaged by the tough inner or pad portion of his fingers and to avoid a scraping or roughening of the rear portions of the holes which in the operation of bowling are positioned opposite to and likely to engage the outer or back and more sensitive portions of the fingers of the bowler.

Having described my invention, I claim:

1. A roughening tool for walls of cylindrical finger-gripping holes of bowling balls embodying, in combination, an elongated blade-mounting housing comprising two parts pivotally connected together at their upper ends to form a handle and having at the lower end of one of said two parts a blade member provided with wall-roughening teeth at one edge, pivot means for mounting said blade member to project outwardly from said housing and to cause the blade edge having said wall-roughening teeth to extend in a plane parallel with one edge of the housing, said housing having in the other of said two parts an integral blade-guiding portion projecting in a direction opposite to said blade and provided with a blunt guiding surface extending in a direction parallel with said blade member, an expansion spring mounted in said housing for normally moving the two parts thereof away from each other, and stop means for limiting said spring-actuated movement, whereby said parts are manually contractible and are adapted upon said spring expansion to cause contact of said toothed edge of the blade with a wall-surface portion of a hole at one side of the axis of the casing and to cause contact of said blunt guiding surface of the said housing with a wall portion of the hole at the opposite side of said axis thereof.

2. A roughening-tool for walls of cylindrical finger-gripping holes of bowling balls as claimed in claim 1, in which the blade-mounting member comprises a pair of integral closely-positioned parallel mounting-jaws, the roughening blade member is mounted intermediate its ends within said jaws on a fixed pivot, and an insertion-stop member projects outwardly from the housing in

spaced relationship above the upper end of the blade to limit insertion movement of the housing into bowling ball finger-gripping hole and to position the roughening blade at the lower portion of said hole.

3. A roughening tool for walls of cylindrical finger-gripping holes of bowling balls embodying, in combination, an elongated blade-mounting housing comprising two parts pivotally connected together at their upper ends to form a handle and having at the lower end of one of said two parts a blade member provided with wall-roughening teeth at one edge, pivot means for mounting said blade member to project outwardly from said housing and to cause the blade edge having said wall-roughening teeth to extend in a plane parallel with one edge of the housing, said housing having in the other of said two parts an integral blade-guiding portion projecting in a direction opposite to said blade and provided with a blunt guiding surface extending in a direction parallel with said blade member, an expansion spring mounted in said housing for normally moving the two parts thereof away from each other, and stop means for limiting said spring- 25 actuated movement, an insertion stop member projecting outwardly from said casing and posi-

tioned above and in spaced relationship to the upper end of the blade to cause the roughening blade to engage a lower portion only of the finger-gripping hole upon insertion therein, said integral blade-guiding portion of the housing being provided with two blunt edges spaced from each other and adapted to contact with the wall surface portions of said hole along two lines positioned at the side of the axis thereof substantially opposite to the wall surface engaged by said blade, whereby a three-line contact is provided with the wall of said cylindrical hole.
